CLAIM

I claim the ornamental design for a protective cover for a mobile payment device, as shown and described.

DESCRIPTION

FIG. 1 is a first perspective view of a protective cover showing my new design;

FIG. 2 is a second perspective view of the protective cover;

FIG. 3 is a left side view thereof;

FIG. 4 is a right side view thereof;

FIG. 5 is a top view thereof;

FIG. 6 is a bottom view thereof;

FIG. 7 is a front view thereof; and,

FIG. 8 is a rear view thereof.

The broken lines shown in FIGS. 1, 2, and 7 is for the purposes of showing environment and forms no part of the claimed design.

1 Claim, 4 Drawing Sheets
